(57) **CLAIM**

I claim the ornamental design for a jewelry clasp, as shown and described.

DESCRIPTION

FIG. 1 is a perspective of one embodiment of a jewelry clasp showing my new design;

FIG. 2 is a top elevation thereof, the bottom elevation being a mirror image thereof;

FIG. 3 is a left end elevation thereof;

FIG. 4 is a right end elevation thereof;

FIG. 5 is a front end elevation thereof;

FIG. 6 is a rear end elevation thereof;

FIG. 7 is a perspective view of a second embodiment of a jewelry clasp of my new design;

FIG. 8 is a top elevation thereof, the bottom elevation being a mirror image thereof;

FIG. 9 is a left end elevation thereof;

FIG. 10 is a right end elevation thereof;

FIG. 11 is a front end elevation thereof;

FIG. 12 is a rear end elevation thereof;

FIG. 13 is a perspective view of a third embodiment of a jewelry clasp of my new design;

FIG. 14 is a top elevation thereof, the bottom elevation being a mirror image thereof;

FIG. 15 is a left end elevation thereof;

FIG. 16 is a right end elevation thereof;

FIG. 17 is a front end elevation thereof; and,

FIG. 18 is a rear end elevation thereof.

The broken lines shown in the drawings form no part of the claimed design.
